CLAIM

The ornamental design for a header for an implantable medical device, as shown and described.

DESCRIPTION

FIG. 1 is a front, right and top perspective view of a header for an implantable medical device;

FIG. 2 is a right side view of the header of FIG. 1;

FIG. 3 is a left side view of the header of FIG. 1;

FIG. 4 is a rear view of the header of FIG. 1;

FIG. 5 is a front view of the header of FIG. 1; and,

FIG. 6 is a top view of the header of FIG. 1.

The broken lines in the drawings depict portions of the header for an implantable medical device that form no part of the claimed design.
